UNITED STATES PATENT OFFICE

SAMUEL SHEINDELMAN, OF LAWRENCE, NEW YORK

DESIGN FOR A SWEATER OR SIMILAR ARTICLE

Application filed January 3, 1933. Serial No. 46,697. Term of patent 3½ years.

To all whom it may concern:

Be it known that I, SAMUEL SHEINDELMAN, a citizen of the United States, residing at Lawrence, Long Island, in the county of Nassau and State of New York, have invented a new, original, and ornamental Design for a Sweater or Similar Article, of which the following is a specification, reference being had to the accompanying drawing, forming part thereof.

Fig. 1 is a perspective view of a sweater or similar article, showing my new design as it appears on the wearer.

Fig. 2 is a back view of the sweater or similar article in flat condition as it appears on the counter.

The front and back of the sweater or similar article are identical in design.

The dominant and essential feature is the body of the garment.

I claim:

The ornamental design for a sweater or similar article as shown and described.

SAMUEL SHEINDELMAN.
